UNITED STATES PATENT OFFICE.

GEORGE M. FAST, OF HAVILAND, OHIO.

SURFACE-PULVERIZER.

1,127,422.

Specification of Letters Patent. Patented Feb. 9, 1915.

Application filed December 31, 1913. Serial No. 809,667.

To all whom it may concern:

Be it known that I, GEORGE M. FAST, a citizen of the United States, residing at Haviland, in the county of Paulding and State of Ohio, have invented a new and useful Surface-Pulverizer, of which the following is a specification.

This invention relates to improvements in surface pulverizers.

An object of the present invention is to provide a surface pulverizer which will thoroughly break up and level the ground over which it passes.

A further object is to provide a surface pulverizer with an adjustable portion so that the depth to which the ground is treated may be varied.

A further object is to provide a surface pulverizer including a plurality of angularly disposed horizontally extending agitators arranged in series, with the angularity of one series opposite to the angularity of the series next adjacent thereto, and to include therewith an adjustable portion which may be raised or lowered and so arranged that the action of the agitators is modified or amplified thereby.

A further object is to provide a surface pulverizer with angularly disposed horizontal extending agitators arranged in series upon the under surface and with parallel cross members arranged along the top surface so that the surface pulverizer may be reversed and the cross members used to smooth the earth and leave it in such condition.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of my invention is illustrated, in which:

Figure 1 is a top plan view of my improved surface pulverizer. Fig. 2 is a cross sectional view thereof taken on the line

Referring to the drawings in which similar reference numerals designate corresponding parts throughout the several figures, 3-3 are spaced side beams between which extend the longitudinally disposed beams 4. The number and spacing of the beams 3 and 4 depends upon the size of the machine and is consistent with the requisite amount of strength and rigidity.

The beams 3 and 4 are formed of angle members and rigidly secured to the lower flanges thereof are the agitators 5. The agitators are arranged in series, extend horizontally, and are inclined at substantially 45 degrees with respect to the transverse median line of the frame defined by the beams 3 and 4. As mentioned the agitators are arranged in a series, each series being composed of a plurality of parallelly disposed agitators extending between two of the longitudinal beams 4. Four series have been illustrated in the present drawings and it is to be noted that the agitators of one series extend at right angles to the agitators of the next adjacent series, and furthermore that the ends of the agitators extend juxtaposed to and approximately central of the agitators of the next adjacent series, as clearly illustrated in Fig. 1. The agitators are formed of angle bars with the one flange thereof extending substantially horizontally and the other extending perpendicularly downward therefrom. The entire frame and agitators are rigidly secured together by suitable rivets 6 or other equivalent means.

Draft bars 7 are rigidly secured to the longitudinal beams 4 and are provided with the hooked ends 8 to which a chain 9 or other equivalent means is secured whereby the draft animal may be secured to the pulverizer and exert a tractive effort thereon.

Projecting rearwardly from the main frame are the eye members 10 to which are pivotally and detachably secured the arms 11. The arms 11 support at their remote extremities an auxiliary frame 12 from which project a plurality of spaced teeth 13. The auxiliary frame and teeth therefore swing about the eyes 10 as a center to thereby extend above or into contact with the soil. In order that the auxiliary frame and teeth may be held in adjusted positions, a segmental bar 14 is provided pivotally secured as at 15 to a bracket 16, the latter being rigidly secured to one of the longitudinal

beams 4. The segmental bar at its remote extremity is provided with the notches 17 which may be engaged by a hand operated latch 18 secured to the lever 19 carried by 5 the auxiliary frame. The lever 19 is provided with the opening 20 extending therethrough receiving the segmental bar 14 therein for the guidance thereof. Thus, when it is desired to raise or lower the teeth 10 13, the hand latch is withdrawn which allows the auxiliary frame to swing about the eyes 10 into some new and desired position. The hand latch is then again inserted in place in engagement with one of the notches 15 17 which securely locks the teeth 13 in any adjusted position with respect to the agitators 5.

Mention is made of the fact that the teeth when approximating the level of the agitators will extend in contact with the ground at pronounced obliquity so that the desired action upon the soil will be obtained.

A detachable seat 21 is positioned upon the main frame and may be moved to any 25 desired position thereon, it resting upon the upstanding flange of the longitudinal beams 4.

The many desirable advantages and features of the present structure will be appreciated by those familiar with the class 30 of agricultural machines to which the present application appertains and the coöperation and coaction between the main and auxiliary frames with their depending teeth and agitators is to be noted.

When the teeth are lowered into contact with the ground, the agitators adjacent the rear of the frame will be raised so that although an acute or harsh scraping action 40 will be obtained adjacent the front of the machine, the same will be modified as the rear of the main frame is approached due to the fact that it will be raised due to the engagement of the teeth 13 with the ground. 45 Thus as the main frame traverses a certain area, the soil coming into contact with the first series of agitators will be broken up and moved to one side in a forcible manner and the second series will produce a similar effect in a more modified manner, until the last series is reached, in which a 50 smoothing action will be obtained after which the teeth 13 will prepare the ground as desired.

55 When it is desired to level the ground and leave the same in a smooth condition the arms 11 are removed from the eyes 10 and the main frame is reversed so that the cross beams 4 will contact with the surface 60 of the ground to produce the desired effect.

Having thus described my invention, what I claim is:—

1. A harrow comprising a frame including side beams, a plurality of angle-shape parallel extending beams secured thereto and arranged with the vertical flange projecting upwardly, a plurality of angle-shaped serially arranged agitators secured to said beams and arranged with the vertical flange extending downwardly. 70

2. A harrow comprising a frame including side beams, a plurality of angle-shape parallel extending beams secured thereto and arranged with the vertical flange projecting upwardly, a plurality of angle-shaped agitators, said agitators arranged in series extending across the frame, the agitators of one series being disposed at right angles to and terminating approximately central of the agitators of the adjacent series. 75

3. A harrow comprising a frame including side beams, a plurality of angle-shape parallel extending beams secured thereto and arranged with the vertical flange projecting upwardly, a plurality of angle-shaped serially arranged agitators secured to said beams and arranged with the vertical flange extending downwardly, and a seat 85 detachably secured to said frame. 90

4. A harrow comprising a reversible frame including side beams, a plurality of angle-shape parallel extending beams secured thereto and arranged with the vertical flange projecting upwardly, a plurality of angle-shaped serially arranged agitators secured to said beams and arranged with the vertical flange extending downwardly, and a seat 95 detachably secured to said frame.

5. A harrow comprising a frame including side beams, a plurality of angle-shaped parallel extending beams secured thereto and arranged with the vertical flange projecting upwardly, a plurality of angle-shaped serially arranged agitators secured 105 to said beams and arranged with the vertical flange extending downwardly, and means secured to the rear extremity of said frame contacting with and supported upon the ground adapted to raise the rear end of 110 said frame and hold the same in adjusted elevated positions.

In testimony that I claim the foregoing as my own, I have hereto affixed my signature in the presence of two witnesses.

GEORGE M. FAST.
